UNITED STATES PATENT OFFICE.

HERBERT W. SYMONDS, OF ST. LOUIS, MISSOURI.

DESIGN FOR A HOT-AIR REGISTER.

45,316.

Specification for Design.

Patented Feb. 24, 1914.

Application filed December 5, 1913. Serial No. 804,941. Term of patent 7 years.

To all whom it may concern:

Be it known that I, HERBERT W. SYMONDS, a citizen of the United States, residing at 1102 Madison street, St. Louis, Missouri, have invented a new, original, and ornamental Design for Hot-Air Registers, of which the following is a specification, reference being had to the accompanying drawing, forming part thereof.

The figure is a front elevation of a hot-air register, showing my new design.

I claim:

The ornamental design for a hot-air register, substantially as shown.

HERBERT W. SYMONDS.
